LUBRICATING MEANS FOR SEWING MACHINES

Max L. Waterman, Fairfield, Conn., assignor to
The Singer Manufacturing Company, Elizabeth, N. J., a corporation of New Jersey

Application July 18, 1935, Serial No. 31,955

7 Claims. (Cl. 112—256)

This invention relates to sewing machines and it has as its primary object to provide improved means for lubricating one or more bearings thereof, such, for example, as the forward bearing of the loop-taker shaft and/or the bobbin-case raceway.

To satisfactorily lubricate those elements of a sewing machine involves problems and difficulties not encountered in the lubrication of other types of machines. Sewing machines are essentially high speed machines. Therefore, the parts must be constantly and adequately lubricated, otherwise undue wear will quickly result. However, due to the nature of the work they perform, this lubrication must be controlled to a nicety, since the slightest over-lubrication will result in soiling the bobbin-thread and consequently in impairment of the product.

Various forms of lubricating means heretofore have been provided for this purpose, but none has been satisfactory in its entirety. Probably the nearest approach to a satisfactory device for the purpose is disclosed in United States patent to Waterman et al., No. 1,689,310, Oct. 30, 1928, of which the present construction is an improvement.

This prior device, although superior to other known devices for the purpose, did not completely solve the problem, and still required frequent attention of the operator which attention, unfortunately, he sometimes neglected to give; it provided no means whereby the operator could be assured of its proper functioning, and, due to its construction, did not positively prevent the lubricant from inadvertently getting on the cloth-plate, especially when the machine was tipped, and consequently the work was likely to be soiled.

More specifically stated, this invention has as an object to provide a lubricating device which will continuously and adequately lubricate the hook-shaft bearing and bobbin-case raceway of a sewing machine for a long period of time without any attention from the operator, and which is so controlled that over-lubrication and impairment of the work is precluded.

Another object is to provide lubricating means for sewing machines, as above described, which, although requiring only infrequent attention of the operator, will, nevertheless, be constantly subject to his scrutiny, whereby he may be assured of the proper functioning of the device and also may readily replenish the supply of lubricant, when necessary.

Still another object of the invention is so to construct the sewing machine frame and so to ar-

range the lubricating means therein that all danger of contact of the work with the lubricant, or the lubricant container, is obviated and the container is effectively protected against breakage.

With the above and other objects in view, as will hereinafter appear, the invention comprises the devices, combination and arrangement of parts hereinafter described and claimed.

The several features of the invention, and the advantages attained thereby will be readily understood from the following description in conjunction with the drawings which have been annexed as a part of this disclosure and which depict a preferred embodiment of the invention.

In the accompanying drawings, Fig. 1 is a side elevation, partly in section, of a portion of a sewing machine showing the improved lubricating means incorporated therein. Fig. 2 represents a horizontal section substantially on the line 2—2 of Fig. 1, with the throat-plate and cloth-plate omitted. Fig. 3 represents a vertical section on the line 3—3 of Fig. 1. Fig. 4 represents an enlarged vertical section on the line 4—4 of Fig. 2, and Fig. 5 a section on the line 5—5 of Fig. 4.

Referring more specifically to the drawings, the invention is disclosed as embodied in a sewing machine comprising a hollow bed 1, an upright standard 2 secured to the bed, and an overhanging arm 3 formed integral with the standard and carrying, at its forward end, the needle-actuating mechanism, cloth-presser and take-up, which, being of conventional form, are not shown. The bed 1 supports a cloth-plate *p* which may be of sheet-metal or other suitable material.

Power to actuate the various mechanisms enters the machine through a shaft 4 journaled in the arm. This power is transmitted by a belt 5 to feeding mechanism, designated generally as *f*, located within the bed 1, and by a belt 6 to a loop-taker shaft 7 journaled in bearings provided by lugs 8 and 9, formed integral with the bed. The forward bearing lug 8 is provided with a bearing bushing 10 having a central bore 11 within which the loop-taker shaft is rotatably journaled. This shaft is formed with an axial bore 12 which is connected through a radial duct 13, formed in a loop-taker 14 secured upon the shaft 7, with a longitudinal duct 15 formed in the loop-taker. The last named duct communicates with an annular raceway 16 within which is journaled a conventional bobbin-case 17. The shaft 7 is also formed, within the bushing 10, with a radial duct 18 extending inwardly from a beveled inlet slot 18^x. At each

rotation of the shaft, this slot is aligned with a duct 19 formed in the bushing and tends to pick up lubricant therefrom. The duct 19 is maintained in permanent communication with a lubricant chamber 20, of relatively small capacity, formed in the bearing lug 8, from which lubricant is received and transmitted through the ducts 19, 18, bore 12, and ducts 13 and 15 to the bobbin-case raceway. Preferably the bore 12 and the ducts 13 and 15 are filled with suitable wicking to somewhat restrict the flow of lubricant therethrough.

To adequately lubricate the forward bearing of the shaft 8, the bore 11 of the bushing 10 is provided with a longitudinal groove 22 which communicates with the radial duct 19 and a peripheral groove 21 in the shaft 1, and receives lubricant therefrom. This bore also is preferably filled with wicking which serves to distribute the lubricant along the bearing.

To prevent the escape of oil from the chamber 20 to the upper surface of the cloth-plate, where it might soil the work, the chamber is preferably closed at its upper end. This may be accomplished in any suitable way, such, for example, as by means of a screw plug 23 threaded therein.

As hereinbefore stated, this invention has as an object to provide a lubricating system which will function for a long period of time without any attention from the operator but which will nevertheless be constantly subject to his inspection and control. This has been attained by the provision of a manually regulatable sight-feed oil-cup 24, of substantial capacity, located remote from the bearing lug 8 and connected with the chamber 20 by a conduit 25. To the end that this oil-cup may be constantly before the operator and still be wholly out of his way and completely protected against breakage and contact with the work, the sewing machine frame has been specially constructed so as to hold within its confines, at the front side thereof, the sight-feed oil-cup.

As shown most clearly in Figs. 1 and 2 the oil-cup is supported upon a bracket 26 secured to the bed 1 and located within a chamber, or cavity, 27 formed therein. This bracket also supports the rearward end of the conduit 25 and is provided with a chamber 26a with which both the oil-cup and the conduit connect. Above the chamber 27 the forward wall of the standard 2 is formed with an inward indentation 28 providing a recess or open face cavity 29 within which the sight-feed oil-cup is located. This cavity is of such dimensions as to wholly receive the oil-cup and yet, as shown by Fig. 3, the depressed forward wall of the standard does not interfere with the driving connections which extend through the standard.

The oil-cup may be of conventional form and is provided with the usual regulating valve, adapted to be controlled by an adjusting nut 30. The oil-cup may also be provided with a conventional cut-off, if desired.

From the foregoing it will be perceived that this invention provides improved means which will continuously and efficiently lubricate bearings of a sewing machine for a long period of time without any attention by the operator; which is constantly under his observation and control, and which is so constructed and arranged as to effectively preclude damage both to the device and to the work being operated on by the sewing machine.

Having thus set forth the nature of the invention, what I claim herein is:—

1. A sewing machine comprising a bed, a standard secured thereto and provided in its forward wall with an open face cavity, a loop-taker shaft journaled in the bed, a loop-taker secured to said shaft and provided with a bobbin-case raceway, and means for supplying lubricant to said raceway comprising a sight-feed oil-cup supported by said bed and located within said cavity and 10 conduit means connecting said oil-cup with said raceway.

2. A sewing machine comprising a bed, a standard secured thereto, vertically aligned chambers formed in said bed and standard, a loop-taker shaft journaled in the bed, a loop-taker secured to said shaft and provided with a bobbin-case raceway, and means for supplying lubricant to said raceway including a supporting bracket located within the chamber in said bed, an oil-cup 20 supported by said bracket and located within the chamber in said standard, and conduit means connecting said oil-cup with said raceway.

3. A sewing machine comprising a bed, a standard secured thereto, said bed and standard having vertically aligned cavities formed therein, a loop-taker shaft journaled in a bearing provided by the bed, a loop-taker secured to said shaft and having therein a bobbin-case raceway, and means for supplying lubricant to said bearing and 30 raceway comprising a supporting bracket secured to the bed and located within the cavity therein, an oil-cup supported by said bracket and located within the cavity in the standard, and conduit means connecting said oil-cup with said bearing 35 and raceway.

4. A sewing machine comprising a bed, a standard having its forward wall locally recessed to form an open face cavity, a drive shaft journaled in said standard, a loop-taker shaft journaled in the bed, a driving connection between said shafts, a loop-taker connected to said loop-taker shaft and provided with a bobbin-case raceway, means for supplying lubricant to said raceway comprising a manually controlled sight-feed oil-cup 45 located within said cavity forwardly of said driving connection, and conduit means connecting said oil-cup with said raceway.

5. A sewing machine frame comprising a bed, an upright standard secured thereto, said standard having a cavity formed in one of its walls, said bed having a complementary cavity located beneath the cavity in said standard, and a supporting bracket, secured to said bed within the cavity formed therein, having a portion fitted 55 within the cavity in the standard and adapted to support, in the last named cavity, a sight-feed oil-cup.

6. A sewing machine having means for lubricating a bearing thereof, comprising a supporting 60 frame provided with an open face cavity, a sight-feed oil-cup located within said cavity and visibly disposed to an operator when in his normal operative position, and conduit means connecting said oil-cup with said bearing.

7. In a sewing machine having a frame comprising a bed and a standard secured thereto, said standard having one of its walls locally recessed to form an open face cavity and said bed supporting a bearing, a lubricating means for said bearing comprising an oil-cup supported by said bed and located within said cavity, and oil conducting means connecting said oil-cup with said bearing.

MAX L. WATERMAN.
